(57) **CLAIM**

The ornamental design for a portable card reader, as shown and described.

DESCRIPTION

FIG. 1 is a perspective view showing a portable card reader that comprises two parts.

FIG. 2 is a perspective view showing a portable card reader that comprises two parts.

FIG. 3 is a front view of a portable card reader bottom.

FIG. 4 is a rear view of a portable card reader bottom.

FIG. 5 is a top view of a portable card reader bottom.

FIG. 6 is a bottom view of a portable card reader bottom.

FIG. 7 is a side view of a portable card reader bottom.

FIG. 8 is a side view of a portable card reader bottom.

FIG. 9 is a front view of a portable card reader top.

FIG. 10 is a rear view of a portable card reader top.

FIG. 11 is a top view of a portable card reader top.

FIG. 12 is a bottom view of a portable card reader top.

FIG. 13 is a side view of a portable card reader top.

FIG. 14 is a side view of a portable card reader top; and,

FIG. 15 is a perspective view showing a portable card reader top.
